UNITED STATES PATENT OFFICE.

CONRAD NEUGEBAUER, OF COLUMBUS, OHIO.

DESIGN FOR A BATH-MITTEN.

58,930.

Specification for Design.

Patented Sept. 6, 1921.

Application filed January 8, 1921. Serial No. 435,994. Term of patent 14 years.

To all whom it may concern:

Be it known that I, CONRAD NEUGEBAUER, a citizen of the United States, residing at Columbus, in the county of Franklin and State of Ohio, have invented a new, original, and ornamental Design for a Bath-Mitten, of which the following is a specification, reference being had to the accompanying drawing, forming part thereof.

The figure is a perspective view of a bath mitten, showing my new design.

I claim:

The ornamental design for a bath mitten, as shown.

CONRAD NEUGEBAUER.
